UNITED STATES PATENT OFFICE.

THOMAS T. STURGES, OF NEW YORK, N. Y.

GAME-TABLE.

SPECIFICATION forming part of Letters Patent No. 344,062, dated June 22, 1886.

Application filed March 15, 1886. Serial No. 195,238. (No model.)

To all whom it may concern:

Be it known that I, THOMAS T. STURGES, of the city and State of New York, have invented an Improvement in Game-Tables, of which the 5 following is a specification.

This invention relates to a table containing a box for holding the chess, checkers, or other games for amusement or recreation, and a reversible panel sliding at its edges into the table-top. On one side of the panel is the checker or chess board, and also a tally-board, such as used in "cribbage," and the other side of the table-top is plain, so that when the sliding panel is reversed the table is adapted to its 15 ordinary use as a side or center table.

This improvement is to be distinguished from the devices heretofore made, in which a table is provided with a drawer and a panel that can be lifted out and reversed, as the 20 drawer is liable to slide out and the panel to fall out when the table-top is turned up vertically and stood aside. It is also to be distinguished from game-boxes that have a sliding cover, but not a surrounding table-top, and when the cover is reversed it does not lie 25 flush with the edges of the box.

In the drawings, Figure 1 is a vertical section of the improved game-table. Fig. 2 is a perspective view of the top with the game-board uppermost, and Fig. 3 shows the usual 30 form of the top.

The box to contain the chess, checkers, or other games is made of a bottom, 1, and sides 2, which form the base or bed of the table-top, and the legs 3 are connected to the box and to the table-top, usually by pivots, so that the 35 table-top and box can be turned up vertically when not in use, as usual. The contour of the table-top may be square, round, oval, or polygonal, as desired, the surface of the top being plain, and the three sides 4 form an open frame, and are connected together and to the box, and there are parallel slideways 5 in the inner 40 edges of the frame, and there is a reversible

panel, 6, with slides on two of its edges, and 45 to which panel one side piece of the frame is fastened, and said panel is made plain on one side, and with the checker or other game board 7 on the other side, and with the tally or cribbage board 8, and the edges of this panel 6 fit 50 the slides 5, and the slide-ribs come in the middle of the edges, so that the panel is flush with the surface of the table-top when either side is up, which is a great convenience in using the table.

The bottom of the box may have the marks usually provided for playing backgammon, the same as often found in checker-board boxes.

I do not claim a table having a number of interchangeable panels, nor do I claim a game-box having a main central box and boxes around it and a reversible panel, upon both sides of which game-boards are placed. In my improved table the smooth level top is adapted to ordinary use, and when the central 65 panel is drawn out and reversed, to bring the chess or checker board uppermost, the side piece of the frame that is connected to the panel fits into the other parts of the frame and is level therewith.

I claim as my invention—

The combination, in a table, of legs, a box supported by the legs, an open frame resting upon and three sides of which are fastened to the box, and having parallel slideways in the 75 inner edges of the frame, a reversible panel with slides on two of its edges, and to which panel one side piece of the frame is fastened, one surface of the panel being plain and the other surface having a chess or other game 80 board, the surface of the panel being level with the surface of the frame when either side is uppermost, substantially as specified.

Signed by me this 3d day of March, 1886.
THOMAS T. STURGES.
